UNITED STATES PATENT OFFICE.

EMANUEL BOSTICK, OF FORT WAYNE, INDIANA, ASSIGNOR TO HIMSELF AND
ERASTUS B. KUNKLE, OF SAME PLACE.

DESIGN FOR AN AGITATING PLATE FOR EGG-BEATERS.

Specification forming part of Design No. 5,296, dated October 3, 1871.

To all whom it may concern:

Be it known that I, EMANUEL BOSTICK, of Fort Wayne, in the county of Allen and State of Indiana, have invented a new and original Design for the Agitating-Plate of an Egg-Beater, of which the following is a specification.

The drawing represents a face view of my new design.

This invention relates to a new form of apertures through the agitating-plate of an egg-beater; and consists in making the same star-shaped. This not only gives a pleasant appearance to the plate, but is also resultive of better effect in operation, as the enlarged edge of each will cause more friction, and consequently more rapid ac-

tion upon the egg, cream, or liquid to be agitated.

A in the drawing represents the working-plate of the egg-beater or equivalent implement made of suitable form. *a a* are the holes cut through it. These holes are star-shaped, as shown. Their number in the plate may be varied at will.

What I claim as my invention is—

The design for the agitating-plate of an egg-beater, as shown.

The above specification of my invention signed by me this 29th day of August, 1871.

Witnesses: EMANUEL BOSTICK.
